UNITED STATES PATENT OFFICE

ERRETT L. CORD, OF CHICAGO, ILLINOIS, AND HERBERT C. SNOW AND DON C. HOLLISTER, OF AUBURN, INDIANA, ASSIGNORS, BY MESNE ASSIGNMENTS, TO AUBURN AUTOMOBILE COMPANY, OF AUBURN, INDIANA, A CORPORATION OF INDIANA

DESIGN FOR AN AUTOMOBILE RADIATOR

Application filed December 8, 1930. Serial No. 37,920. Term of patent 7 years.

● *To all whom it may concern:*

Be it known that we, ERRETT L. CORD, a citizen of the United States, and a resident of Chicago, Illinois, HERBERT C. SNOW, a citizen of the United States, and a resident of Auburn, Indiana, and DON C. HOLLISTER, a citizen of the United States, and a resident of Auburn, Indiana, have invented a new, original, and ornamental Design for an Automobile Radiator, of which the following is a specification, reference being had to the accompanying drawings, forming a part thereof, in which Fig. 1 is a perspective view of an automobile radiator showing our new design

and Fig. 2 is a view in front elevation of the same.

We claim:—

The ornamental design for an automobile radiator substantially as shown.

In testimony whereof, I have hereunto set my hand, this 21st day of November, 1930.

ERRETT L. CORD.

In testimony whereof, I have hereunto set my hand, this 21st day of November, 1930.

HERBERT C. SNOW.

In testimony whereof, I have hereunto set my hand, this 21st day of November, 1930.

DON C. HOLLISTER.
